UNITED STATES PATENT OFFICE.

THOMAS W. SMITH, OF SCRANTON, PENNSYLVANIA.

LUBRICATOR.

1,171,361.

Specification of Letters Patent.

Patented Feb. 8, 1916.

Application filed February 16, 1915. Serial No. 3,536.

To all whom it may concern:

Be it known that I, THOMAS W. SMITH, citizen of the United States, residing at Scranton, in the county of Lackawanna and 5 State of Pennsylvania, have invented new and useful Improvements in Lubricators, of which the following is a specification.

My present invention relates to piston-rod lubricators, and is designed more especially as an improvement on the lubricator 10 disclosed in my Letters Patent No. 929,039 of July 27, 1909.

One object of the present invention is to diminish the cost of manufacture of the 15 lubricators, and to reduce to a minimum the expense for repairs and renewals, by providing a lubricator that is calculated through the medium of reducers to be nicely fitted to piston rods of various diameters.

20 Another object of the invention is the provision of a piston-rod lubricator embodying improved means for taking lubricant from the hollow body and applying the same to the piston rod.

25 Another object is the provision of a lubricator embodying body sections so constructed and relatively arranged that they are interlocked or held together of themselves.

Other advantageous features of the 30 invention will be fully understood from the following description and claims when the same are read in connection with the drawings, accompanying and forming part of this specification, in which:

35 Figure 1 is a front elevation of the lubricator constituting the preferred embodiment of my invention. Fig. 2 is a vertical section taken through the hollow portion of the body and showing the reducers and the 40 lubricant-applying means in said hollow portion. Fig. 3 is a horizontal section taken on the line 3—3 of Fig. 1, looking downwardly. Fig. 4 is a rear elevation showing the dove-tail joint between the two 45 sections of the body. Fig. 5 comprises separated views of the two reducers embodied in the device; the upper reducer being shown in side elevation, and the lower reducer in longitudinal section.

50 Similar numerals of reference designate corresponding parts in all of the views of the drawings.

The lubricator body may be and preferably is made of cast-iron or other cheap

material. It is preferably, though not necessarily, formed in two sections, as shown. The upper section comprises a hollow portion 1, of dove-tail form in outline, entirely open at its lower side and having a filling opening 2 in its top wall, and a flange plate 3 that forms a continuation of the back wall of the hollow portion 1, and has a dove-tail opening 4 in its lower portion to receive and fit over the dove-tail hollow body portion 5 of the lower section, and also has 60 apertures 6, the latter for the passage of screws or bolts through which the lubricator is to be connected with the usual gland at one end of a piston cylinder.

In addition to the hollow portion 5 of 70 dove-tail form in outline, the lower body section comprises a flange plate 7 that is arranged in a plane slightly in front of the back wall of the portion 5 and has a dove-tail-shaped opening 8 in its upper portion 75 designed to fit snugly over and receive the hollow portion 1 of the upper body portion. By virtue of the described relative arrangement of the two body sections, it will be manifest that they will be interlocked and 80 held together of themselves, so that the device can be conveniently placed and adjusted on a piston rod; also, that when so interlocked, the plate 7 of the lower body section will rest in front of and close against the 85 plate 3 of the upper body section, Fig. 3.

The hollow portion 5 of the lower body section is closed at its bottom, and its upper end is entirely open and is opposed to the lower open end of the hollow portion 1 90 complementary to the upper body section. The front walls of said portions 5 and 1 rest in flush relation.

95 Interiorly the upper hollow portion 1 is provided with an integral semi-circular partition wall 9 having a central seat 10 and a central aperture 11, and at the ends of said wall 9 said portion 1 is provided with seats 12.

The lower hollow portion 5 is provided 100 with an integral semi-circular partition wall 13 somewhat similar to the wall 9; the said wall 13 having, preferably but not necessarily, a central aperture 14 and also having a central seat 15, and apertures 16 105 located near its ends. At the ends of the wall 13 the lower hollow portion 5 is provided with seats 17.

The reducers 18 and 19 of the lubricator are preferably made of comparatively soft material such as copper or brass, and it will be understood that the scheme of my invention contemplates the employment of reducers of different sizes to fit the lubricator to piston rods of different diameters; also, that it is purposed when one or a pair of reducers is worn or otherwise impaired to replace the reducer or reducers with new ones without loss of the lubricator as a whole.

The reducers 18 and 19 are identical in construction. Each of said reducers 18 and 19 is of open-work construction *i. e.*, has spaced side bars 20, Fig. 5, and each is provided with a central apertured projection 21 designed to rest in the central seat of one of the partition walls 9 or 13, and end projections 22 designed to rest in the end seats 12 or 17 of one of the hollow portions of the body sections. It will also be observed by reference to Fig. 3, that the openwork portions 21^x, Fig. 5, of the reducers that bear the projections 21 and 22 are of reduced width, this to afford flanges 23 that are designed to be opposed to the edges of the front and back walls of the hollow portions 1 and 5.

30 The hollow portions 1 and 5 are designed to hold lubricant; the lubricant being supplied through the opening 2 which may be provided with an approved closure (not shown).

35 Arranged in the hollow portion 1 of the upper body section are wicks 30 which are threaded through the aperture 11 and have portions at opposite sides of the partition 9. The lower portions of the said wicks are 40 designed to rest against and supply lubricant to a semi-circular packing section 31, arranged and held in the upper reducer. The said wicks are designed to siphon lubricant from the interior of the upper hollow portion 1 to the packing section 31 which, in turn, is adapted to apply the lubricant to 45 the piston rod (not shown).

50 Against the upper side of the partition wall 13 in the lower hollow portion 5 is arranged a wick 32. This wick has a looped portion 33 depending through the aperture 14, and also has end portions extending through the apertures 16 and depending in the interior of the portion 5. This wick by 55 siphon action supplies lubricant to a semi-circular packing section 34 arranged and held in the lower reducer, and designed to coöperate with the section 31 in applying lubricant to a piston rod.

60 The wicks and the packing sections described are readily removable and renewable.

65 It will be gathered from the foregoing that either of the reducers 18 or 20 may be replaced with a new reducer when worn or

impaired; also, that by using thicker reducers in lieu of those illustrated the device may be readily fitted to a piston rod of small size in cross-section.

I would also have it understood that when 70 deemed necessary, the lower hollow portion 5 may be provided with a complementary filling aperture and closure means therefor. These, however, I have deemed it unnecessary to illustrate, inasmuch as they are not essential 75 to the successful operation of my novel lubricator.

Having described my invention, what I claim and desire to secure by Letters-Patent, is:

1. In a lubricator, a body comprising sections each of which has a hollow portion, of dove-tail form in outline, open at its inner end and also has a flange provided with a dove-tail opening; the sections being interlocked with the dovetail opening in the flange of one snugly receiving the dovetail hollow portion of the other and with the open ends of the hollow portions opposed.

2. In a lubricator, the combination of hollow body portions having opposed inner ends and also having semi-circular apertured partition walls and also having central and end seats, semi-circular open-work reducers removably arranged in the inner 90 ends of the hollow body portions and against the partition walls and having projections disposed in said seats, wicks extending through the apertures of the partition walls and arranged at the inner sides of said 100 walls, and semi-circular packing sections arranged in the reducers and against said wicks.

3. In a lubricator, the combination of hollow body portions having opposed inner ends, removable and renewable reducers arranged in said inner ends of the body portion, packing means arranged in said reducers, and means for transferring lubricant from the interiors of the body portions 105 to the packing means.

4. In a lubricator, the combination of hollow body portions having opposed inner ends, removable and renewable reducers arranged in said inner ends of the body portion, semi-circular packing sections removably arranged in said reducers, and means for transferring lubricant from the interiors of the hollow body portions to the packing sections.

5. The combination in a lubricator, of a hollow body having inner and outer compartments, reducing means arranged in the inner compartment of the body, packing means in the reducing means, and means for transferring lubricant from the outer compartments of the body to the packing means.

6. The combination in a lubricator, of a hollow body having inner and outer compartments, reducing means arranged in the 130

inner compartment of the body, packing means in the reducing means, and wicks carried by the reducers and arranged in contact with the packing means and also arranged in the outer compartments of the body.

In testimony whereof I have hereunto set

my hand in presence of two subscribing witnesses.

THOMAS W. SMITH.
